UNITED STATES PATENT OFFICE.

RAYMOND C. LONGVALL, OF WORCESTER, MASSACHUSETTS, ASSIGNOR TO WARP COM-
PRESSING MACHINE COMPANY, OF WORCESTER, MASSACHUSETTS, A CORPORATION
OF MASSACHUSETTS.

CREEL OR SPOOL STAND.

Application filed January 5, 1925. Serial No. 637.

To all whom it may concern:

Be it known that I, RAYMOND C. LONGVALL, a citizen of the United States, residing at Worcester, in the county of Worcester and Commonwealth of Massachusetts, have invented a new and useful Improvement 5 in a Creel or Spool Stand, of which the following, together with the accompanying drawings, is a specification.

10 My invention relates to creels or spool stands, such as are employed for rotatably supporting a plurality of spools or yarn packages so that the yarn or thread may be conveniently led therefrom for winding on 15 a wrap beam, or for any other purpose.

The object of my invention is to provide an improved creel, or spool stand, in which a large number of spools or packages may be mounted so as to occupy a minimum 20 amount of floor space, and in which the spools or packages can be readily doffed and replenished. My invention contemplates a creel comprising a number of similar sections in each of which the thread 25 guides and thread boards are so arranged that all of the threads from one or more given series of spindles may be lifted by a single operation so as to enable the operator to doff the exhausted packages and replace them with fresh packages without 30 disturbing the remainder of the threads handled by the creel. The above and other advantageous features of my invention will hereinafter more fully appear, reference 35 being had to the accompanying drawings in which.

Fig. 1 is a plan view of a complete creel or spool stand embodying my invention.

Fig. 2 is a view in end elevation showing 40 one of the sections of the creel of Fig. 1, on an enlarged scale.

Fig. 3 is a perspective view of a portion of the section shown in Fig. 2 and illustrating the position normally occupied by 45 the thread guides and thread boards.

Fig. 4 is a perspective view illustrating the position occupied by the thread guides and the thread boards when doffing.

Fig. 5 is a diagrammatic view illustrating 50 the passage of the threads from a given row of supplies.

Like reference characters refer to like parts in the different figures.

Referring to Fig. 1, the improved creel

comprises a number of sections numbered 55 1, 2 and 3, arranged in tandem, it being obvious however, that any other desired number of creel sections may be employed. The creel sections 1, 2 and 3 are substantially identical in construction, so that it 60 will only be necessary to describe the first section 1 in detail, for a complete understanding of my invention.

Referring now to Figs. 2 and 3, each creel section consists of a number of spaced uprights 4 carrying oppositely extending pairs of spindles 5, 5. The spindles 5 of one upright 4 are in horizontal alinement with the spindles 5 of the other uprights 4, thus providing a number of alined series of 70 spindles 5 in different horizontal planes. The spindles 5 are adapted to receive spools or yarn packages 6, from which the threads 7 are led to my improved thread guiding and handling mechanism which will now be 75 described.

As best shown in Fig. 3, a number of bars 8 are supported between vertical standards 9, the number of bars 8 corresponding to the number of horizontal rows 80 of spindles 5 and each bar 8 being provided with thread eyes 10 corresponding in number and in spacing to the spindles 5 in a given row. Each bar 8 is carried by arms 11 pivotally attached to the standards 85 9, and during the normal operation of the creel the arms 11 hang downwardly to bring the thread eyes 10 of each arm in substantial alinement with the spaced spindles 5 of the corresponding row. With 90 this arrangement each thread 7 is taken off its package 6 symmetrically with respect to the axis of the corresponding spindle 5, and all of the threads 7 from a given row of 95 spindles 5 are thus disposed in substantially the same horizontal plane as they are drawn through the thread eyes 10.

A thread board 12 is suitably secured to each bar 8 and one of its supporting arms 11, with the plane of the board 12 substantially at right angles to that portion of the bar 8 in which the thread eyes 10 are carried. The thread board 12 is provided with a number of vertically spaced rows of 100 thread eyes 13, 14 and 15, the eyes 13 in 105 the upper row lying in substantially the same plane as the eyes 10 of the corresponding bar 8. The several threads 7 passing

through the eyes 10 of a given bar 8 are thus adapted to pass through the upper row of eyes 13 of the corresponding thread board 12 in more or less sheet form and 5 without interfering with each other, suitable tensioning devices 16 of a well known type being interposed between the eyes 10 and 13, if desired.

From a joint consideration of Figs. 1 10 and 3, it will be seen that the number of rows of eyes 13, 14 and 15, carried by each thread board 12 of the forward section 1 corresponds to the number of sections, it being obvious that the number of sections 15 and spindles employed can be increased or decreased as desired without departing from my invention. As previously stated, the sections 1, 2 and 3 are substantially identical in construction, corresponding parts being numbered the same and the only difference being that the thread boards 17 of the second section 2 are provided with one less row of eyes 18 and 19 than the thread boards 12 of the first section 1, as best shown in Fig. 3. 20 Similarly the thread boards 20 of the last section 3 are provided with one less row of eyes 21 than the second section 2.

From the foregoing description it is apparent that the threads 7 drawn from any given horizontal row of spindles in all of the creel sections will pass through the eyes 13, 18 and 21 of the corresponding thread boards 12, 17 and 20, respectively, in substantially the same horizontal plane, and 30 without interference from each other, as indicated diagrammatically in Fig. 5. In passing from a thread board 20 the threads from the rearmost section 3 are deflected downward slightly to pass through first the eyes 19 of a thread board 17, and then through the eyes 15 of a thread board 12. Correspondingly, the threads passing from a thread board 17 of the next preceding section 2 are deflected downward slightly to 40 pass through the eyes 14 of a thread board 12, so that all threads from a given row of spindles pass from the creel in three closely spaced planes and without interference with each other.

50 When it is desired to doff packages on any given row of spindles in a section, the thread board of the corresponding row is lifted, as indicated in Fig. 4, which shows, for example, a portion of the first section. 55 When the thread board 12 is lifted as shown, it moves about the pivotal support of the arms 11 and carries with it the attached bar 8 and the eyes 10, thus moving all of the threads passing through the bar 8 above the 60 plane of the corresponding set of spindles 5. With the bar 8 in its raised position it is evident that the exhausted spindles or packages can readily be doffed and the spindles replenished without interfering with the 65 threads passing through the lower rows of

eyes 14 and 15 of the thread board 12, which are, of course, lifted with the threads passing through the upper row of eyes 13. In order to maintain a thread board 12 and its associated bar 8 in a raised position, each 70 thread board 12 is provided with a pivotally mounted prop 22 which normally hangs downwardly, as shown in Fig. 3, and is adapted to be turned to engage the standard 9 and thus hold the thread board in its elevated position, as shown in Fig. 4. When it is desired to lower the thread board and bar after doffing it is only necessary to turn the prop 22 downwardly, whereupon the thread board 12 will return to its normal horizontal position, as shown in Fig. 3. 80

While it is evident that any one of the thread boards 12, 17 and 20 may be raised independently of all other thread boards in the creel, my invention contemplates means 85 whereby the raising of a particular thread board and bar will cause one or more of the thread boards immediately above it to also be raised a limited amount so as to prevent any interference between the threads of the spindles being doffed and the threads of the spindles immediately above. To this end each thread board is provided with laterally extending ears 23, which, as best shown in Fig. 4, are adapted to engage the lower edge 90 of the thread board immediately above when the lower thread board has been raised a predetermined amount. This action is fully illustrated in Fig. 2, in which one of the lowermost thread boards 12 has been completely raised to the doffing position, thereby lifting the two thread boards 12 immediately above it a limited amount, which in this case is not enough to disturb the third thread board from the one being raised. 100 It is obvious that the vertical spacing between the rows of spindles in any creel may be such as to result in the raising of two or more thread boards in unison, or the vertical spacing may be such as to permit each thread board to be fully raised without engaging the thread board immediately above it. 110

115 It will be observed that in any case, movement of one or more thread boards or bars in nowise slackens the tension on any thread, nor allows any thread to hang down loosely, but rather, as will be clearly seen from Fig. 4, keeps each and every thread in a taut condition, for the reason that the eyes 10, as a 120 thread board 12 and bar 8 are moved into the doffing position, move away from the corresponding spindles 5. This feature of my invention is of considerable advantage, as it eliminates the possibility of tangling. 125

From the foregoing, it is apparent that by my invention I have provided an improved creel, or spool stand, so arranged that one or more horizontal rows of spindles may be readily doffed and replenished without inter- 130

fering with the threads coming from the other spindles of the creel. Furthermore, a creel embodying my invention lends itself to a very compact arrangement of spindles and packages owing to the ease with which any number of spindles can be doffed; consequently creels embodying my invention occupy a minimum amount of floor space.

I claim,

1. In a device of the class described, a plurality of spindles arranged in rows, means for maintaining the threads from a row of spindles in substantially the same plane, and means for shifting a number of threads from a given row of spindles into another plane to permit doffing, while keeping each thread in a substantially taut condition.

2. In a device of the class described, a plurality of spindles arranged in rows, means for maintaining the threads from a row of spindles in substantially the same plane, and means for shifting a number of threads from a given row of spindles into another plane without disturbing the threads from spindles in other rows.

3. In a device of the class described, a plurality of spindles arranged in rows, means for maintaining the threads from a row of spindles in substantially the same plane, and means for shifting a number of threads from a given row of spindles into another plane without disturbing the threads from the balance of the spindles in the same row.

4. In a device of the class described, a plurality of spindles arranged in rows, a plurality of thread guiding devices arranged in rows corresponding to said spindles, for receiving threads from said spindles, and means for simultaneously shifting a number of said thread guiding devices out of alignment with the corresponding spindles, said means also moving said thread guiding devices further from said spindles.

5. In a device of the class described, a plurality of spindles arranged in rows, a plurality of thread guiding devices arranged in rows corresponding to said spindles, for receiving threads from said spindles, and means for simultaneously lifting a number of said thread guiding devices above and away from the corresponding row of spindles.

6. In a device of the class described, a plurality of spindles arranged in rows, and a plurality of bars each providing a series

of eyes for receiving threads from a number of spindles in a given row, and each bar being adapted to swing a limited distance about a horizontal pivotal axis independently of the other bars.

7. In a device of the class described, a plurality of spindles arranged in rows, and a plurality of bars each providing a series of eyes for receiving threads from a number of spindles in a given row, and each bar being adapted to swing about a horizontal pivotal axis to lift the thread eyes when doffing.

8. In a device of the class described, a plurality of spindles arranged in rows, and a plurality of bars each providing a series of eyes for receiving threads from a number of spindles in a given row, and each bar being adapted to swing about a pivotal axis to shift the plane of the threads passing through the corresponding eyes, while keeping said threads substantially in a plane.

9. In a device of the class described, a plurality of spindles arranged in rows, a plurality of pivotally mounted bars each providing a series of eyes for receiving threads from a number of spindles in a given row, and a thread board movable with one of said bars for simultaneously shifting the threads coming from more than one of said bars.

10. In a device of the class described, a plurality of spindles arranged in rows, a plurality of pivotally mounted bars each providing a series of eyes for receiving threads from a number of spindles in a given row, and thread boards movable with said bars and extending substantially at right angles thereto for receiving the threads coming from more than one bar in a row of spindles.

11. In a device of the class described, a plurality of spindles arranged in rows, a plurality of pivotally mounted bars each providing a series of eyes for receiving threads from a number of spindles in a given row, and thread boards movable with said bars and extending substantially at right angles thereto for receiving the threads coming from more than one bar in a row of spindles, movement of one thread board and its bar being adapted to cause movement of the thread board and bar next above. Dated December 26, 1924.

RAYMOND C. LONGVALL.
